UNITED STATES PATENT OFFICE.

ROSCOE P. BUFFINGTON, OF BALTIMORE, MARYLAND.

SANITARY BOTTLE-STOPPER.

1,208,089.

Specification of Letters Patent. Patented Dec. 12, 1916.

Application filed May 22, 1916. Serial No. 99,039.

To all whom it may concern:

Be it known that I, Roscoe P. Buffington, a citizen of the United States, residing at Baltimore city, State of Maryland, have 5 invented certain new and useful Improvements in Sanitary Bottle-Stoppers, of which the following is a specification.

This invention relates to bottle seals, and more particularly to an improvement in the 10 seal shown in my Patent No. 1160571, dated November 16, 1915.

The object of the invention is to provide a bottle seal which is entirely devoid of metal parts, and which is provided with an 15 outlet to permit the contents of the bottle to be poured out without removing the seal. The outlet is provided with a closure, and these parts are so arranged that the contents of the bottle do not come in contact with any 20 portion of the seal which may have been touched by the person's fingers, thus removing all danger of contamination.

The invention also has for its object to simplify the device disclosed in the patent 25 referred to.

In order that the invention may be better understood, reference is had to the accompanying drawing in which—

Figure 1 is a plan view of the device; Fig. 30 2 is a cross-section thereof in position on the bottle; Fig. 3 is a section showing the bottle inverted to pour out its contents; Fig. 4 is a plan view of the sealing disk, and Fig. 5 is a plan view of a closure.

35 In carrying out the invention, there is provided a circular disk 6 of pasteboard or similar material which is dimensioned to fit tightly in the mouth of the bottle 7, the same having the usual internal shoulder 8 on 40 which the disk seats. The disk 6 has a central opening 9 providing an outlet through which the contents of the bottle may be discharged as shown in Fig. 3. The area of the outlet 9 is such that it may also serve as a 45 vent, thus obviating the necessity of providing the disk with an additional opening for this purpose.

On top of the disk 6 is mounted a closure for the outlet opening 9, this closure being 50 a disk 10 having the same contour as the disk 6. Off to one side of the center of the disk 10 is a crease shown by the dotted line 11. This crease extends entirely across the disk and divides the same into two segments. 55 The smaller one 12 of these segments is permanently fixed to the disk 6 below the outlet

opening by being pasted thereon in any suitable manner, forming a sealed joint between the two disks at the edge of the pouring opening, leaving the larger segment 13 free 60 of the disk 6 and serving as a flap to cover the opening 9. The crease 11 forms a closed hinge connection between the segments to allow the larger segment which forms the closing flap for the opening 9 to be swung 65 open and closed, and to facilitate the operation of the flap, the same is provided with a small tab 14 extending from the edge of the flap, the tab being integral with the flap and being foldable over on top thereof as 70 shown in Figs. 1 and 2. To facilitate the folding of the tab, there is made a transverse crease in the paper at the junction of the tab and the body of the flap, this crease being shown by the dotted line 15 in Fig. 75 5. The tab also has a central longitudinal crease 16 so that it may be folded on this line when it is grasped to operate the flap.

When the device is in sealing position, the disk 6, with the disk 10 on top thereof and 80 closing the opening 9, are in the bottle mouth as shown in Fig. 2, the tab 14 being also folded down, so that there is nothing projecting from the bottle mouth. To pour out the contents of the bottle, the tab 14 is 85 grasped, and the flap 13 is pulled outward to uncover the opening 9, whereupon the bottle may be tilted to pour out its contents as shown in Fig. 3. The bottle will be so positioned that the flap hangs down, so that 90 it now serves as a pouring spout or lip. It will also be noted that the liquid comes in contact with the under side of the flap, and the tab is behind the flap, in view of which it will be evident that there is no danger of 95 the liquid becoming contaminated by coming in contact with any portion of the device which may have been handled.

The disk 10 will be made of paraffined 100 paper of sufficient thickness to serve the purpose for which it is designed. As the smaller segment 12 is permanently fixed to the disk 6, the crease 11 forms a substantial hinge joint for the flap formed by the larger segment 13, and said flap, when swung down to cover the opening 9, seats tightly in the bottle mouth and thus forms an efficient closure preventing dust, dirt, insects, etc., from getting into the bottle. No metallic parts are necessary, the entire device being formed of 110 paper or pasteboard. The structure is also simple and inexpensive and the cost of the

device will be but slightly greater than that of an ordinary sealing cap such as used on milk bottles.

I claim:

- 5 A bottle seal, comprising a disk provided with a pouring opening having a relatively wide pouring edge, and a combined cover and pouring lip for said disk and opening, said cover and pouring lip having a closed 10 hinged joint formed across the same and a

closed connection with said disk, both said closed hinged joint and closed connection with the disk being positioned adjacent said wide pouring edge.

In testimony whereof I affix my signature 15 in presence of two witnesses.

ROSCOE P. BUFFINGTON.
